GAGE FOR LIQUID-CONTAINING TANKS.

1,201,527.

Specification of Letters Patent.

Patented Oct. 17, 1916.

Application filed November 25, 1914. Serial No. 874,063.

To all whom it may concern:

Be it known that I, PERRY E. TANNER, a citizen of the United States, residing at Akron, in the county of Summit and State of Ohio, have invented a certain new and useful Improvement in Gages for Liquid-Containing Tanks, of which the following is a full, clear, and exact description, reference being had to the accompanying drawings.

This invention relates to gages for liquid containing tanks, whereby the height of liquid in the tank is indicated upon a dial so as to be observed at a glance.

The objects of the present invention are the provision of a device of this character which can be applied to a tank of awkward or irregular construction; the provision of an instrument which can be installed through a very small or tortuous opening; the provision of an instrument which can be adjusted for tanks of different sizes, shapes, and angles; the provision of new and improved expedients for preventing the liquid in the tank from leaking into the dial chamber; the provision of a device of great simplicity, cheapness and reliability; while further objects and advantages will appear as the description proceeds.

Generally speaking my invention may be defined as consisting of the combinations and construction recited in the claims here-to annexed and illustrated, in one embodiment, in the drawings accompanying and forming part of this specification, wherein:

Figure 1 is a cross sectional view taken through a tank equipped with my improved gage; Fig. 2 is a longitudinal cross sectional view through the gage proper; Fig. 3 is a perspective view of the inner end of the gage tube; and Fig. 4 is an enlarged detail sectional view showing the leak-preventing means.

Describing the parts by reference characters 1 represents a tank, which is here shown as of oval shape as is frequently used upon the rear of automobiles of the present day. Owing to the particular shape and arrangement of this tank, my improved gage offers peculiar advantages when used therewith although it will be understood that my gage could be used with other tanks with complete satisfaction although without exhibiting all of the advantages present in this combination.

At the upper part of the tank 1 I have

shown a forwardly and upwardly extending neck 2 having at its side a filling opening 3 closed by a threaded cap 4. The end of the neck 2 is provided with a screw threaded ring 5 receiving the gland nut 6 which cooperates with a suitable abutment ring or shoulder 7 carried by the tube interior in securing in place a cylindrical gage head 8. While my gage is not limited for use with necks of this character, such a neck is of frequent occurrence in connection with tanks and I have provided a gage which can be used conveniently with the same. The gage head 8 preferably consists of a cylindrical metal shell having walls 10 and a back 11, the latter carrying a hollow tube 12 adapted to extend through the neck 2 and into the tank. Projecting axially through this tube is a movable spindle 13 which passes through a suitable aperture in the back 11 and through a perforation in a suitable supporting plug 14 at the inner end of the tube. The forward or outward end of this spindle is provided with a suitable indicating hand or pointer 15 adapted to cooperate with a suitable scale 16 mounted within the head.

To the inner end of this spindle is attached the float stem 17 having at its free end the float 18. At a point adjacent to the spindle 13 this stem is coiled upon itself as shown at 19 to provide a helix preferably having its axis transverse to the stem 17 and preferably substantially intersecting the same. In the present embodiment the spindle 13 and stem 17 are shown as formed of different pieces of metal, the stem, after being wound into the helix 19, being bent into U shape as shown at 20 so as to receive the deflected end 21 of the spindle which is then secured thereto by soldering, brazing, or in any other convenient manner. This arrangement permits the spindle and stem to be made of wire of different sizes, and is a convenience in point of manufacture, although not indispensable to my invention.

In order to prevent leakage through the tube 12 and into the indicator head, and also to prevent any appreciable end shift of the spindle 13, I have adopted the arrangement shown in Figs. 2 and 4 hereof. This arrangement consists of a hollow cup-shaped member 25 of a size and shape to be fitted closely inside the tube 12 as by a pressed joint, and having its end closed by a plug 26 suitably secured therein, preferably by a pressed joint also. This plug 26

together with the bottom 27 of the cup are formed with alined apertures for the passage of the spindle 13, such apertures being internally threaded for the reception of threads 28 with which the spindle is provided at this point. This cup is filled with a suitable packing composition which shall coöperate with the threaded engagement in preventing leakage of liquid along the tube. 5 I have used a kind of soft soap with good results, and I have also used a composition of glycerin and graphite, but do not restrict myself to either of these materials since any viscous material of suitable hardness and 10 adhesiveness may be employed, provided that it is not soluble in the liquid with which the tank is filled. The materials above suggested are suitable for use with gasoline. Owing to the necessity that the threads in 15 the apertures must be continuous it is necessary to cut them after the plug 26 has been secured in place and before the cup or cavity is filled with the packing material. This material is preferably introduced into the 20 cavity of the cup 25 by means of a small syringe immediately prior to the introduction of the spindle.

In order to limit the movement of the spindle, which is necessary in the case of 25 an automobile tank to protect the pointer from being damaged by the thrashing of the float, I have illustrated a wire clip 30 arranged to be sprung about the end of the tube 12 and provided with a pair of spaced 30 forwardly projecting fingers 31, 31 arranged to coöperate with the portion 20, 21 in limiting the movement of the spindle. This clip may be secured in place by soldering or any other suitable means.

40 The great advantages of this device are the simplicity and cheapness, the fact that it can be inserted into a tank through any kind of tortuous opening because of the elasticity given by the helix 19, and the fact 45 that by bending the stem 17 so as to increase or decrease the angle between the same and the spindle 13 the gage can be adapted for tanks of different shapes, heights, and widths.

50 It will be understood that many changes in detail can be made in my invention within the terms of the claims hereto annexed.

Having thus described my invention, what I claim is:—

55 1. A gage for liquid containing tanks, comprising a hollow tube adapted to be secured in the tank wall and having a hollow head at its outer end, a rotatable spindle in said tube, an indicating device carried 60 by said spindle inside said head, a float operatively connected to said spindle, and a leakage preventing member carried by said tube and through which said spindle passes, said member having a pair of apertured 65 walls defining a cavity, such cavity contain-

ing a fluid packing substance insoluble in the liquid of the tank, and the spindle and apertures being formed with intermeshing threads.

2. A leakage preventing member for 70 liquid tank gages of the rotary spindle type, said member comprising a hollow box having alined threaded apertures in opposite walls thereof through which said spindle passes, such box being filled with a fluid 75 packing substance insoluble in the liquid of the tank, and said spindle having threads meshing with the threads of said apertures.

3. A gage for liquid containing tanks, comprising a hollow member adapted to be 80 secured in one of the tank walls and having a hollow head at its outer end, a rotatable spindle in said tube, an indicating device in 85 said head and connected to said spindle, a fixed member inside said hollow member and having an internally threaded bore through which said spindle passes, said spindle having external threads meshing with the threads in said bore whereby leakage therealong is prevented and appreciable 90 longitudinal movement of the spindle is avoided, and a float operatively connected to said spindle.

4. A gage for liquid containing tanks, comprising a hollow member adapted to be 95 secured in one of the tank walls and having a hollow head at its outer end, a rotatable spindle in said tube, an indicating device in 100 said head and connected to said spindle, a fixed member inside said hollow member and having an internally threaded bore through which said spindle passes, said spindle having external threads meshing with the threads in said bore whereby appreciable 105 longitudinal movement of the spindle is avoided, said member having a cavity intermediate its ends and through which said spindle passes, and a fluid packing material in said cavity insoluble in the tank liquid.

5. A gage for liquid containing tanks 110 comprising a hollow member adapted to project therein, a rotatable spindle therein, means for securing said member in the tank wall, an indicating device connected to the outer end of said spindle, a flexible stem 115 connected directly to the inner end of said spindle and projecting angularly therefrom, said stem having a helical resilient portion adjacent to its point of connection with said spindle and transverse thereto, and a float carried by said stem.

6. A gage for liquid containing tanks 120 comprising a hollow member adapted to project therein, a rotatable spindle therein, means for securing said member in the tank wall, an indicating device connected to the outer end of said spindle, a flexible stem 125 connected directly to the inner end of said spindle and projecting angularly therefrom, said stem having a helical resilient portion whose 130

axis is transverse to said spindle and substantially intersects the same, and a float carried by said stem.

7. A gage for liquid containing tanks comprising a hollow member adapted to be secured in the tank wall, a rotatable spindle in said member, an indicating device attached to the outer end of said spindle, a resilient helix attached to the inner end of said spindle with its axis transverse thereto, a stem connected to said helix, and a float carried by said stem.

8. In liquid gage of the type comprising a rotatable member, a stem projecting angularly therefrom and a float carried by said stem, the combination with said member and stem of a resilient helix arranged therebetween and having its axis transverse to said member.

9. The combination with the stem of a liquid float, of a resilient helix connected in said stem adjacent to the pivotal point thereof and having its axis substantially perpendicular to the pivot axis.

10. A gage for liquid containing tanks comprising a hollow tube adapted to be secured in the tank wall and having a hollow head at its outer end, indicating devices in

said head, a rotatable spindle journaled in said tube and connected to said indicating devices, a wire stem attached directly to the inner end of said spindle and projecting therefrom at an angle, and fingers connected to said tube at its inner end and projecting upon opposite sides of said stem connection and adapted to limit the movement thereof.

11. A gage for liquid containing tanks comprising a hollow member adapted to project therein, a rotatable spindle arranged therein and projecting through the inner end thereof, an indicating device connected to the outer end of said spindle, a float, a stem to which said float is attached, said stem being connected to the inwardly projecting end of the spindle, said stem being coiled adjacent said point of connection, the axis of said coil being at right angles to the axis of the spindle, whereby a joint is provided flexible in one direction but rigid in a direction transverse thereto.

In testimony whereof, I hereunto affix my signature in the presence of two witnesses.

PERRY E. TANNER.
